UNITED STATES PATENT OFFICE.

THOMAS WRIGHT, OF JERSEY CITY, NEW JERSEY.

DUMPING-WAGON.

1,139,945.

Specification of Letters Patent. Patented May 18, 1915.

Application filed December 17, 1912. Serial No. 737,800.

To all whom it may concern:

Be it known that I, THOMAS WRIGHT, a citizen of the United States, residing at Jersey City, in the county of Hudson and State of New Jersey, have invented a new and useful Dumping-Wagon, of which the following is a specification.

This invention relates to dumping wagons of the back delivery type, the principal object of the invention being to provide a body adapted to be placed on motor trucks and which has means whereby a short quick dump of the body can be effected, simple and efficient means being provided for shifting 10 said body into and out of dumping position.

A further object is to provide a dumping wagon having normally inactive rollers which are shiftable by the operator into or out of active position to provide means 20 whereby when the rollers are in active position, the body can be shifted readily into or out of dumping position and, when they are in inactive position, the body will rest upon the frame of the wagon and thus be held 25 against accidental displacement.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without 35 departing from the spirit of the invention.

In the accompanying drawings the preferred form of the invention has been shown.

In said drawings:—Figure 1 is a side elevation of a portion of a dumping wagon 40 having the present improvements combined therewith, the body being shown in its normal position, the position assumed by said body when dumping, being indicated by dotted lines. Fig. 2 is a rear elevation of 45 the parts shown in Fig. 1. Fig. 3 is a plan view of a portion of the body actuating mechanism. Fig. 4 is a side elevation of one of the rollers and adjacent parts, one position of the roller being indicated by dotted 50 lines. Fig. 5 is a side elevation of a slightly modified form of mechanism wherein the rollers are connected to the body and the rail on which the rollers travel is shiftable upwardly and downwardly to raise and 55 lower the body relative to the frame.

Referring to the figures by characters of

reference A designates a portion of the vehicle frame or chassis which can be of any standard construction and the structure constituting the present invention is adapted 60 to be mounted upon this chassis. This structure includes transverse bolsters B which are arranged on the frame or chassis A and which constitute supports for rails 1 which extend longitudinally above the frame 65 A and have their rear ends curved downwardly, as at 2 and preferably secured, as at 3, to the sides of the frame A. A shaft 4 is journaled upon the lower edges of the rails 1 and extends transversely thereof, the ends 70 of the shaft projecting beyond the outer sides of the rails and being preferably angular, as shown at 5, so as to be engaged and rotated by means of a suitable crank, 75 not shown.

Secured to shaft 4 near each end thereof, is a small gear 6 arranged close to the outer face of the adjacent rail 1, each gear meshing with a rack bar 7 secured to an elongated slide 8 mounted upon the outer side of the 80 adjacent rail 1. This slide is held against the rail 1 by guide lugs 9 and 10, a single lug 9 being located directly above gear 6 while a pair of lugs 10 are arranged on one side of rail 1 at a distance from lug 9 substantially equal to the length of the rack bar 7. A slot 11 is formed in each slide close to the rack bar 7 and projecting into this slot is a connecting pin 12 extending inwardly from one end of an elongated link 90 13, the other end of the link being pivotally connected, as at 14, to a bracket 15. The brackets 15 to which the two links 13 are attached, are secured to the bottom of the dumping body 16 of the wagon and adjacent 95 the sides of the body. Furthermore these brackets are not attached to the center of the sides of the bottom but are attached to the bottom at points between the rear end of the body and the transverse center thereof, the distance between the rear end of the body and the brackets 15 being slightly greater than one-third the length of the body.

It is to be understood that under normal 105 conditions the body 16 bears downwardly on the rails 1. The frictional engagement of the body with the rails will thus be such as to prevent the body from shifting accidentally out of normal position. When, 110 however, it is desired to dump the body, it is of course necessary to lift the body out of

frictional engagement with the parts thereunder. One means for elevating the body has been illustrated in Figs. 3 and 4. This means includes a transverse shaft 16' adapted to be rotated in any suitable manner and provided with a gear 17 meshing with a larger gear 18 secured to a second transverse shaft 19. The shafts 16' and 19 are journaled upon the lower edge portions of the rails 1 and a small gear 20 is carried by shaft 19 adjacent the inner side of each rail 1 and is engaged by a rack bar 21. Each rack bar is pivotally connected, as at 22, to parallel bars 23 extending rearwardly adjacent the inner side of the rails 1, these bars 23 being connected, at desired intervals, by transverse rods 24, each rod extending through both bars of each pair. Mounted on each rod 24 and between the bars of each pair are rollers 25 and links 26 are connected to the inner sides of the rails 1 and are also connected to the rods 24. Thus it will be seen that when the rack bars 21 are shifted in one direction, they will push upon the bars 23 and cause the links 26 to swing upwardly about their fulcrums, thus elevating the rollers 25 above the upper edges of the rails 1 and into contact with the body 16 to elevate the body out of contact with the rails. By shifting the rack bars 21 in the opposite direction, the rollers 25 will be swung downwardly into position below the upper edges of the rails 1 and the body 16 will therefore be lowered into contact with the rails.

When it is desired to dump the body 16, the operator rotates shaft 16' by any suitable means provided for that purpose and as this shaft is provided with a small gear 17 which meshes with a large gear 18, it will be apparent that considerable leverage will thus be obtained so that shaft 19, when rotated, will cause gears 20 to actuate the rack bars 21 and thus push against all of the links 26 through bars 23. The power thus obtained will be sufficient to elevate the body 16 out of contact with the rails 1. After the rollers 25 have thus been brought to active positions, shaft 5 is rotated in one direction and the gears 6 thereon will push the rack bars 7 rearwardly, thus causing the slide 8 to also move rearwardly. After the center of the body passes the point indicated at *a* in Fig. 1, said body will begin to swing downwardly upon the curved portions 2 of the rails 1 so that a short quick dump of the body is thus effected.

When the body reaches dumping position, the slides 8 move into recesses 27 formed in the sides of the rails 1 near the curved portions 2 and thus limit the rearward movement of the body relative to the rails. After the contents of the body have been discharged, the said body can be readily brought back onto the rails by reversing the

movement of the shaft 5 so as to cause the gears 6 to pull on the rack bars 7. The body will swing downwardly onto the rollers 25 and be drawn forwardly, the rollers acting as anti-friction devices for facilitating such movement. As soon as the body has been brought forward to its initial position, the rollers 25 are lowered in the manner hereinbefore described, thus permitting the body to gravitate onto the rails 1.

While it is preferred to have the rollers mounted in the manner hereinbefore described, it is to be understood, that if desired, the rollers, shown at 28, can be mounted in brackets 29 fixedly connected to the body 30. These rollers bear downwardly on a track 30' supported by links 31 and rack bars 32 are connected to the track and are engaged by gears 33 corresponding with the gears 20 hereinbefore described. Thus it will be seen that by shifting the rack bars in one direction, the track 30' will be elevated so as thus to lift the body out of contact with the rails 1. When the rack bars are shifted in the opposite direction, the track will be lowered and the body 30 thus permitted to gravitate onto the rails 1.

Especial importance is attached to the fact that, in the present structure, the body, while dumping, does not swing about a fixed pivot but rolls along the downwardly curved rear terminals of the rails 1, this action resulting in a short quick dump which is much more desirable than a dump such as is effected where the body swings about a fixed pivot.

As hereinbefore stated the present improvements are in the form of an attachment to be applied to the chassis of a truck already constructed. In the structure shown, for example, in Fig. 5, all parts of the mechanism including the means for elevating the body 30 are carried by the rails 1. While this is not true of the structure shown in Figs. 1, 2, 3 and 4, the pivots of the links 26 being shown connected to a chassis A, it is to be understood that this connection can be effected readily or, if desired, a bracket such as shown at 29 in Fig. 5 may be employed and the links 26 connected to the bracket instead of to the chassis A.

What is claimed is:—

1. A dumping attachment for trucks, including rails having downwardly curved spaced rear terminals adapted to lap the sides of and be secured to the chassis of a truck, means extending transversely under the rails for engaging said chassis to support the rails, a body normally bearing downwardly on the rails, gearing supported by the rails and below the upper edges thereof, means operated by the gearing and connected to the body for shifting said body longitudinally of the rails in both directions, and means carried solely by said rails for

lifting the body off of the rails to facilitate the longitudinal movement of the body.

2. An attachment for the chassis of a motor vehicle, said attachment including rails having their rear ends turned downwardly and adapted to be secured to the rear portion of a chassis insertible therebetween, a slide upon the outer side of each rail, guide lugs outstanding from the rails for holding the slides to the rails, a rack bar carried by each slide, a shaft journaled upon the rails, means revoluble with the shaft and engaging the racks for shifting the slides simul-

taneously in the direction of the length of the rails, a link slidably and pivotally connected to each slide, and a dumping body normally bearing upon the rails, said links being pivotally connected to the body.

In testimony that I claim the foregoing as my own, I have hereto affixed my signature in the presence of two witnesses.

THOMAS WRIGHT.
